LEAK STOPPER FOR CONDENSER TUBES

Samuel Pennella, East Orange, N. J.

Application February 21, 1941, Serial No. 380,003

3 Claims. (Cl. 138—97)

This invention relates to condenser tubes, and more particularly to leak stopping inserts for insertion into a condenser tube for preventing leakage through openings formed in the tubes by corrosion or erosion.

The cooling water flowing through the tubes of a surface condenser causes failure of the inlet ends of the tubes, due to impingement, erosion and electro-chemical corrosion, resulting in the eating away and perforation of the tube, causing leakage. Such action has been found by experience to be most severe in close proximity to the inlet end of the tube. It has been the practice heretofore to replace such leaking tubes at a considerable expense both in cost of new tubes, cost of the operation of re-tubing of the condenser, and also in the resultant loss of tubes which have only a short part of their entire length rendered incapable of proper operation.

It is an object of the present invention to provide an insert or leak-stopping sleeve for insertion into the "eaten away" end of the tube for effectively sealing any leaks therein, consequently prolonging the life of the tube, as well as eliminating for a practical period of time the necessity for re-tubing the condenser.

It is necessary, to stop such leaks and prevent further deterioration of the tubes, that the leak stopping insert or sleeve fit the interior of the tube in fluid tight engagement, and necessary also that the act of forcing the insert into the tube not disrupt or break the corroded tube. An object of the present invention is to provide a novel, practical insert which can be readily forced into a corroded tube without disrupting or rupturing the tube structure, which will effectively stop all leaks in the tube, and one which will not impair the heat transfer efficiency of the condenser by adversely affecting the cooling water flow through the tubes.

More specifically, the present invention comprises a leak stopping insert of sufficient hardness and density to permit it to be accurately machined, yet one which will swell or expand when wetted or moistened, so as to tightly fit within the condenser tube and form a fluid tight engagement with the interior of the condenser tube. This fiber tube is lined with a metal sleeve, preferably of the same metal as that which is employed in the condenser tube. This metal sleeve prevents internal expansion of the fiber sleeve and permits free unimpeded flow of cooling water through the condenser tube.

With these and other objects in view, as may appear from the accompanying specification, the 55

invention consists of various features of construction and combination of parts, which will be first described in connection with the accompanying drawing, showing a leak-stopper for condenser tubes of the preferred form embodying the invention, and the features forming the invention will be specifically pointed out in the claims.

In the drawing:

10 Figure 1 is a view, partly in section, of a condenser tube, illustrating the manner in which it is "eaten away" by erosion and corrosion.

15 Figure 2 is a longitudinal section through a condenser tube showing the improved leak-stopping insert therein.

Figure 3 is a cross-section on the line 3—3 of Figure 2.

Figure 4 is a fragmentary longitudinal section through a modified form of the invention.

20 Referring more particularly to the drawing, 1 indicates a water circulating tube of a surface condenser which has been attacked by both erosion and corrosion, causing an eating away of parts of the interior of the condenser tube, as shown at 2. Such eating away of the condenser tube eventually causes openings or perforations, as indicated at 3, in the tube, resulting in leakage of circulating cooling water into the condensing space of the condenser and pollution of 25 the condensate as well as decreasing the heat transfer efficiency of the surface condenser.

30 This corrosion of the condenser tubes, it has been found, occurs at and adjacent to the inlet end of the tubes, resulting in the spoiling of only 35 a short section of the entire length of the tube. However, it is the practice, when the inlet ends of such tubes are eaten away, to remove the entire tube and replace it with a new tube, incurring considerable expense occasioned by the purchase of new tubes, the removal of the old tubes 40 and the retubing of the condenser, as well as the loss of the major portion of the corroded tubes.

The present invention comprehends an insert 45 which may be inserted into the condenser tube to form an inner wall for the corroded portion of the tube and stop the leakage of the circulating cooling water through the openings in the tube caused by the corrosion or erosion. When the tube is eaten away to such an extent that it is porous or has holes therethrough, the walls of the tube are necessarily weakened. To provide an effective stoppage of the leaks and to prevent further corrosion and erosion of the tube, it is necessary that the leak stopping insert be in fluid tight engagement with the tube.

If the leak stopping insert is of sufficient size to form a fluid tight engagement with the inner wall of the tube, the driving of such insert into the tube is quite apt to rupture the eaten away portion of the tube, resulting in the necessity of replacing the tube. The present invention provides an insert which will not only prevent rupturing of the eaten away or weakened portion of the tube, but will also form a firm, secure, fluid tight connection with the tube, effectively preventing any leakage.

The insert, generically indicated by the numeral 10, comprises an outer sleeve 11, formed of fibrous material of sufficient hardness and density to permit it to be accurately machined. It is turned so that its outer diameter is slightly less than the inner diameter of the condenser tube 1. Thus it may be easily driven or forced into the condenser tube without undue strain upon the weakened tube portion. The fibrous material is of such nature that when it is wetted or becomes moist it will swell sufficiently to form a firm, secure, fluid tight engagement with the inner surface of the condenser tube 1, effectively sealing off any leakage of circulating water from the tube as well as effectively preventing the leakage of any circulating cooling water between the facing surfaces of the condenser tube and the leak stopping insert. The fibrous material sleeve is prevented from inward expansion by a metal sleeve 12, which is driven or forced tightly into the interior of the fibrous sleeve 11, forming an inner metal wall for the reinforced portion of the condenser tube. The metal sleeve 12 is preferably made of the same material as is the material of which the condenser tube 1 is formed. The thickness of the leak stopping insert 10 gradually decreases as it approaches the outlet end of the insert, as shown at 14 in Figure 2 of the drawing, forming a slightly increased outlet which gradually merges into the line of the interior bore or diameter of the tube 1 so as to prevent the formation of eddies at the outlet of the insert.

In Figure 4 a slightly modified construction of the invention is shown in which a second leak stopping tube or insert of larger diameter is employed for securely holding the insert in a con-

denser tube having an enlarged or belled inlet end. In this modified form the condenser tube 20 has its inlet end 21 enlarged or belled. To permit manufacture of standard sizes of stop leak inserts, a stop leak insert 22 of the same construction as shown in Figures 2 and 3 of the drawing is inserted into the condenser tube, and a second insert, shown at 23, is forced over the outer surface of the insert 22 in the enlarged or belled end 21 of the tube 20. This second or larger insert 23 comprises a sleeve 24 of the fibrous material, which has a metal lining sleeve 25 therein. This metal lining sleeve 25 contacts the fibrous sleeve 26 of the insert 22 and is firmly held thereon in fluid tight engagement upon the expansion of the fibrous sleeve 26 due to its being moistened or wetted. The outer fibrous sleeve 24 of the insert 23 fits tightly against and in fluid tight engagement with the inner wall of the enlarged end 21 of the tube 20.

It will be understood that the invention is not to be limited to the specific construction or arrangement of parts shown, but that they may be widely modified within the invention defined by the claims.

What is claimed is:

1. Means for stopping leaks in a condenser tube perforated by corrosion or erosion comprising a tubular insert of a hard compact fibrous material subject to swelling or expansion when wetted, and a metal sleeve within said fibrous tubular insert, said fibrous material swelling upon wetting to seal leaks in a tube.

2. Means for stopping leaks in a condenser tube perforated by corrosion or erosion comprising a tubular insert of hard compact fibrous material subject to swelling or expansion when wetted, and a metal sleeve within said fibrous by its swelling action upon wetting, and means within said tubular insert to restrain the tubular insert from swelling inwardly.

3. The combination with a condenser tube perforated by corrosion or erosion, of a tubular insert of hard compact fibrous material subject to swelling or expansion when wetted, inserted into said condenser tube and swelling upon wetting to seal the leaks in the tube.

SAMUEL PENNELL.

CERTIFICATE OF CORRECTION.

Patent No. 2,262,042.

November 11, 1941.

SAMUEL PENNELIA.

It is hereby certified that error appears in the printed specification of the above numbered patent requiring correction as follows: Page 2, second column, line 38, claim 2, strike out the comma and words ", and a metal sleeve within said fibrous" and insert instead --and serving to seal such leaks in the tube--; and that the said Letters Patent should be read with this correction therein that the same may conform to the record of the case in the Patent Office.

Signed and sealed this 30th day of May, A. D. 1944.
